Patented Oct. 26, 1965

202,676

STAND FOR A PLURALITY OF VENDING MACHINES

Norman G. Weitzman, 16401 Knapp St., Sepulveda, Calif.

Filed July 10, 1964, Ser. No. 80,798

Term of patent 14 years

(Cl. D80—9)

FIG. 1

FIG. 2

FIG.3

FIG.4

FIG.5

FIG. 1 is a perspective view of a stand for a plurality of vending machines, showing my new design;

FIG. 2 is a right side elevational view thereof;

FIG. 3 is a rear elevational view thereof;

FIG. 4 is a top plan view thereof; and

FIG. 5 is a bottom plan view thereof.

The broken-line representation of vending machines in FIGS. 1, 2, and 3 are for purposes of illustration only.

I claim:

The ornamental design for a stand for a plurality of vending machines, substantially as shown and described.
